UNITED STATES PATENT OFFICE.

JOHN H. RIEDELL AND LEMUEL W. LITCH, OF LYNN, MASSACHUSETTS.

MACHINE FOR MAKING BOX-TOES AND STIFFENERS FOR BOOTS AND SHOES.

SPECIFICATION forming part of Letters Patent No. 337,082, dated March 2, 1886.

Application filed November 12, 1885. Serial No. 182,546. (No model.)

To all whom it may concern:

Be it known that we, JOHN H. RIEDELL and LEMUEL W. LITCH, both of Lynn, in the county of Essex and State of Massachusetts, have invented certain new and useful Improvements in Machines for Making Box-Toes, &c., of which the following is a specification.

This invention has for its object to provide an automatic machine for performing the successive operations of cutting out blanks for box-toes, heel-stiffeners, and other analogous articles from sheets or strips of leather-board or other material usually employed for such purposes, molding said blanks into the shape required, and, if desired, perforating them for the reception of the attaching devices in case box-toes are being made, and for crimping the flanges in case counter-stiffeners are being made.

20. The invention consists as a whole in an organized machine comprising guiding and feeding mechanism for the strips of the material from which the blanks are cut, dies for cutting out the blanks from said strips, a rotative plate or carrier having a series of pockets which receive the blanks as they are cut out, means for rotating said plate or carrier step by step, dies for forming said blanks into the desired shape, and devices for ejecting the completed articles from the machine.

The invention also consists in the several details and combinations of parts, all of which we will now proceed to describe and claim.

Of the accompanying drawings, forming a part of this specification, Figure 1 represents a front elevation of the machine embodying our invention. Fig. 2 represents a side elevation of the same. Fig. 3 represents a top view of the rotative carrier plate, the guides, and the feeding mechanism. Fig. 4 represents a section on line $\alpha\alpha$ of Fig. 3. Fig. 5 represents a bottom plan view of the mechanism for rotating the carrier plate, said plate being shown in dotted lines. Fig. 6 represents a section on line yy of Fig. 3. Fig. 7 represents a section on line zz of Fig. 3. Fig. 8 represents a perspective view of the head or plunger, showing the dies which cut out, mold, and perforate blanks for box-toes, said head 50 and its dies being shown in an inverted position. Fig. 9 represents a perspective view of

the box-toe formed by the machine. Fig. 10 represents a plan view of the rotative carrier-plate as formed for making counter-stiffeners. Fig. 11 represents a section on line $x'x'$ of Fig. 5, showing also the movable die which co-operates with the fixed die shown in plan on Fig. 10. Fig. 12 represents an end view of the movable die shown in Fig. 11. Fig. 13 represents a section on line yy' of Fig. 10, showing also the movable die which co-operates with the fixed die shown in Fig. 10. Fig. 14 represents an end view of the movable die shown in section in Fig. 13. Fig. 15 represents a perspective view of the heel-stiffener formed by the devices shown in Figs. 10, 11, 12, 13, and 14.

The same letters of reference indicate the same parts in all the figures.

In the drawings, a represents the supporting frame of the machine, in which is journaled a vertical arbor, b , to the upper end of which is affixed a plate, c , which is preferably circular, and is provided with a concentric series of pockets, d , formed to receive the blanks which are cut from a strip of material, as hereinafter described.

e represents an arm affixed to the frame a , and having on its upper surface adjustable parallel flanges ff , said arm and the flanges ff constituting a guide for the strip g of leather-board, or other suitable material, from which the box-toes or other like articles are to be formed by the machine.

i represents a feed roll, preferably having a serrated periphery, and arranged to bear against the under side of the strip of material resting on the arm e and received between the flanges ff , said roll being rotated step by step by mechanism hereinafter described.

At the inner end of the flanges ff is a fixed plate, j , having a female die, k , which is shown in Fig. 1 as of the form required to make a box-toe. The rotative plate c is rotated step by step, and when it is at rest one of its pockets d exactly coincides with the female die k , the plate c being under said die, so that the pocket coinciding therewith will receive a blank formed by the combined action of said female die k and the male die, to be presently described.

In the upper portion of the frame a are ver-

tical guides g' , in which is fitted to slide a plunger, l , having at its lower end a cross-head, m , to which are affixed a male punching-die, n , (formed to co-operate with the female die $5 k$), a male forming-die, o , which co-operates with a female forming-die, p , in the frame of the machine under the rotative plate c , and the pair of punches or perforators $q q$, which are adapted to form the perforations $q' q'$ in the box-toe, as shown in Fig. 9. Said dies and punches are so arranged that at each descent of the cross-head m the dies n and o and the punches $q q$ will act simultaneously, the die n entering the female die k and cutting out a blank from the strip of material placed over the die k , while the punches $q q$ pass through a blank in another pocket which has been moved by the rotation of the plate away from the point where the blanks are cut, and the die o enters another pocket, which has been brought by the rotation of the plate c over the female forming-die p , as shown in Fig. 7, the dies o and p co-operating in molding the blank in the pocket into which the die o descends.

25 From the foregoing it will be seen that the strip from which the articles are made is moved forward over the female die k , and a blank is punched therefrom by each descent of the die n , each blank being forced by the die n into the pocket d in the rotative plate c , held in position to receive such blank. As soon as the blank is cut out and deposited in a pocket of the plate c , said plate is partially rotated to bring another pocket into position under the die k , and to carry the blank already cut forward to a position under the punches or perforators $q q$. Said punches are in the present instance arranged so that two steps or partial rotations of the plate c are required to move the blank from the die k to a position under said punches. The punches descending form the holes $q' q'$ in the blank, and the perforated blank is then carried forward by another partial rotation of the plate c , to a position over the female forming-die p and under the male forming-die o . The die o descending acts upon the blank under it, pressing said blank into the die p , as shown in Fig. 7, and giving it its complete form.

50 We prefer to place a spring or ejector, f' , in a cavity in the bed of the frame containing the die p , said spring being adapted to yield to the descending movement of the die o , and being projected when the die o rises, so that it will loosen or raise the formed blank. The next partial rotation of the plate c brings the formed blank in contact with a spring-finger, r , which is pivoted at s to a stud affixed to the frame of the machine and is pressed by a spring, t , against the periphery of the plate c . In the periphery of said plate is a series of recesses, u , corresponding in number to the pockets d , and said recesses are so arranged that when each pocket with the formed blank has reached a point in suitable proximity to the spring-finger r a recess, u , will arrive at the point of bearing of the finger r against the periphery

of the plate c , and will permit said finger to be pressed by its spring t in the direction indicated by the arrow in Fig. 3. This movement of the finger r will cause it to throw off the completed blank from the plate c , said blank falling through an opening, a' , in the frame of the machine. A hood should be placed over said opening to guide the ejected blank into the opening. Said hood is omitted in the drawings for the sake of clearness.

The cross-head m and the operative parts carried thereby are reciprocated by means of an eccentric on a horizontal shaft, b' , journaled in the upper portion of the frame a , said eccentric being shown in dotted lines in Fig. 2. The shaft b' is provided with a gear, s' , meshing with the similar gear or pinion, s , on the driving-shaft c' , to which power is applied by a belt or otherwise.

r' represents a slide adapted to move vertically in guides $g' g'$ on the frame of the machine. To said slide is affixed an angular arm, f' , having a vertical portion, to which is affixed a ruck, g' , meshing with a pinion, h' , on an arbor, i' , journaled in bearings on the frame of the machine.

j' represents a rack, which slides in guides in the frame of the machine under the rotative plate c , and has a series of teeth at its upper side at one end meshing with the pinion h' , and another series of vertical teeth, k' , near its opposite end, meshing with the pinion l' , which is placed upon the arbor b of the rotative plate c , so as to rotate loosely on said arbor. The pinion l' is provided with two dogs, m' , which are pressed by springs against the toothed periphery of a ratchet, n' , affixed rigidly to the arbor b .

At one end of the arbor i' is a bevel pinion, o' , meshing with a similar pinion, p' , which is attached to a plate or disk, v' , mounted to rotate loosely on the arbor r' , to which the feed-roll t is affixed, and provided with a dog, a' , engaging with the ratchet b' , affixed to the arbor r' .

The continuous rotation of the arbor b' , reciprocating the cross-head m and the ratchet b' affixed thereto causes the pinion h' and the arbor i' to rock or oscillate. The pinion h' is thus caused to reciprocate the rack j' , the teeth k' of which oscillate the pinion l' and cause the dogs m' thereon to alternately slip upon and engage with the teeth of the ratchet n' , thus rotating said ratchet and the arbor b and the rotative plate c step by step.

The oscillations of the bevel-pinion o' cause the bevel-pinion p' and the plate v' to oscillate in like manner and the dog a' to alternately slip upon and engage the teeth of the ratchet b' , thus rotating the arbor r' and feed-roll t intermittently or step by step.

We prefer to place a loose roll, d' , over the feed-roll t to press the strip g upon the serrated surface of said feed-roll, the roll d' being preferably coated with yielding material, such as rubber.

To prevent the blanks from sticking to the

punches or perforators q , we provide a spring clearing-plate, c , (shown in Figs. 6 and 8,) which pushes the blank from the punches when the latter rise.

5 In Figs. 10, 11, 12, 13, and 14 we have shown the punches and cutting-out and forming dies adapted to make a heel-stiffener of substantially the form shown in Fig. 15. In this case the blanks are cut out, forced in the pockets 10 of the plate c , and carried forward by the successive rotations of said plate in the manner already described; but instead of employing the punches or perforators q we substitute for said punches a male die, i , formed as 15 shown in Figs. 11 and 12, to crimp or corrugate and bevel the edge of the blank which subsequently forms the flange, k , and in the fixed bed under the plate c we form a female die, l , formed to co-operate with the die i in 20 crimping and beveling the edge of the blank. The male forming-die has a rounded end, (shown in section in Fig. 13 and in end elevation in Fig. 14,) and the female forming-die p is correspondingly rounded, as shown in Fig. 25 13, so that the descent of the die o into the die p will bend the blank into the form shown in Figs. 13 and 15.

It will be borne in mind that the margin of the blank which forms the flange is crimped 30 and beveled before the blank reaches the forming-dies o and p , the crimping and beveling operation facilitating the bending or forming of the blank by said dies o and p .

Our invention is not limited to the details 35 of mechanism herein described, as said details may be variously modified without departing from the spirit of the invention. We do not limit ourselves to a rotative carrier-plate, as said plate may be arranged to move in a recti- 40 linear direction, if desired, in which case the cutting and forming dies would be arranged substantially in line with each other instead of having the concentric arrangement herein shown. The machine may be adapted to form 45 other articles which are capable of being molded from sheets of material analogous to leather or leather-board.

The machine is provided with suitable stop motion, by which its operation can be readily 50 controlled by the attendant, said motion being of any well-known or suitable construction.

We claim as of our invention—

1. In a machine for forming box-toes or 55 other like articles, the combination of the fixed female cutting-die, the reciprocating male cutting-die, a movable plate or carrier under said dies, having a series of pockets formed to receive the articles cut out by said dies, mech- 60 anism, substantially as described, for moving said carrier progressively step by step and holding it after each movement in position to receive a blank in one of its nocks from the

cutting-dies, a fixed bed under the carrier, containing a female forming-die arranged to coincide with a pocket of the carrier at each stoppage of the latter, and a reciprocating male forming-die arranged to pass through the pocket in the carrier, eject the blank therefrom, and press said blank into the female die, 65 70 as set forth.

2. The combination of the fixed female cutting-die, the reciprocating male cutting-die, the intermittently-operating feed mechanism, whereby a strip of material is automatically supplied to said dies, a movable plate or carrier under said dies, having a series of pockets formed to receive the articles cut out by said dies, mechanism, substantially as described, for moving said carrier progressively 75 step by step and holding it after each movement in position to receive a blank in one of its pockets from the cutting-dies, a fixed bed under the carrier, containing a female forming-die arranged to coincide with a pocket of 80 the carrier at each stoppage of the latter, and a reciprocating male forming-die arranged to pass through the pocket in the carrier, to eject the blank therefrom, and press said blank into the female die, as set forth. 85

3. The combination of the feed mechanism for moving a strip forward step by step, the plate or carrier provided with a series of pockets, the cutting dies arranged over said plate to cut blanks from a strip of material presented by the feeding mechanism and to force 90 said blanks into the pockets of the plate, punches or perforators arranged to act on the blanks after they have been removed from the cutting-dies, and forming-dies arranged to act 95 on the said blank after they have been punched or perforated, as set forth.

4. The combination of the rotative plate having a series of pockets and a corresponding series of recesses in its periphery, the cutting and forming dies arranged and operated substantially as described, and the spring-finger bearing with a yielding pressure against the periphery of the plate and caused by the notches therein to spring inwardly over the 100 plate at intervals and remove the formed blanks therefrom, as set forth. 105

5. The combination of the carrier or plate having a series of pockets, the cutting-dies, the male crimping-die i , the female crimping-die l , and the forming-dies o and p , substantially as set forth. 115

In testimony whereof we have signed our names to this specification, in the presence of two subscribing witnesses, this 9th day of November, 1885. 120

JOHN H. RIEDELL.
